UNITED STATES PATENT OFFICE.

THADDEUS CAHILL, OF NEW YORK, N. Y.

PIANOFORTE-ACTION.

SPECIFICATION forming part of Letters Patent No. 554,108, dated February 4, 1896.

Application filed March 21, 1893. Serial No. 467,097. (No model.)

To all whom it may concern:

Be it known that I, THADDEUS CAHILL, a citizen of the United States, and a resident of the city, county, and State of New York, but 5 residing temporarily at Washington, in the District of Columbia, have invented certain new and useful Improvements in Pianoforte-Actions, of which the following is a specification.

10 The object of my invention is to construct a simple, durable, and perfect power pianoforte-action, and more particularly to reduce to a minimum the power required to impel the friction-driver; and my invention consists in the parts, improvements and combinations hereinafter described and claimed.

The concrete structure herein described in illustration of my invention consists of (a) a rotating, circular friction - driver, traction-20 shaft or tractor; (b) a hammer, mounted upon a hammer-shank, and having a curved hammer-butt, the curved surface of which lies normally in close proximity to the surface of the friction-driver, traction-shaft or tractor, 25 said hammer-butt serving as a contact-piece to take power from the friction-driver for the impelling of the hammer; (c) a pressure-lever or hammer-butt carrier, upon which the before-mentioned hammer-butt is mounted and 30 by which the curved surface of said hammer-butt is pressed against the traction-shaft or tractor when the key is depressed; (d) escapement mechanism whereby the hammer is released from the tractor or friction-driver after 35 it is moved by the same; (e) checking mechanism, whereby the rebound of the hammer is broken, and it is prevented from striking the string more than once for each depression of the key; and (f) means for mounting the 40 friction-driver so as to reduce to a minimum the power required to impel said part.

The present application relates only to the means for mounting the friction-driver.

The construction of hammer, curved hammer-butt, pressure-lever carrying the hammer-butt, escapement and checking mechanism illustrated in the drawings (and described herein as an illustration of what I mean by a "friction-driver action") forms the 45 subject-matter of another application of even date herewith, Serial No. 467,096.

In the accompanying drawings, Figure 1 is

a front elevation of the main frame of the action with the friction-driver and its mountings, the other parts being removed. Fig. 2 55 is a sectional view in elevation on the plane of the line x x in Fig. 1, illustrating the friction-driver, its mountings, and its connection with the hammer and other parts of the action. Fig. 3 is a detail sectional elevation, 60 on a larger scale than the other figures, illustrating more clearly a portion of the mechanism shown in Fig. 2. Fig. 4 is a side elevation of the main frame and parts mounted thereon. Fig. 5 is a detail sectional elevation on the line y y , Fig. 1. Fig. 6 is a detail elevation illustrating a modified construction, and Fig. 7 is a detail view in sectional elevation illustrating another modification. Fig. 8 is a front elevation similar to Fig. 1, 70 but illustrating a modification in which the friction-driver is supported by supporting-wheels at each end instead of under its middle, and in which the friction-driver is mounted in vertically-movable boxes, its ends resting upon the inside surface of rims formed upon the supporting-wheels, which latter are mounted upon fixed axles. Fig. 9 is a view similar to Fig. 8, but partly in section and with the bars that hold the retaining-boxes 75 or retaining-bearings of the friction-driver in place removed to show such bearings. Fig. 10 is a sectional view in elevation on the line x x , Fig. 8, looking to the left of said figure; and Fig. 11 is a similar view on the same 80 line, but looking to the right of the figure.

The main frame of the action consists essentially of upright or vertical ribs A A, connected together by an upper horizontal rib, A', and a lower horizontal rib, A'', said ribs A' 90 and A'' being also connected by shorter vertical ribs A³ and A⁴. Said main frame is made of cast-iron or other suitable material and is attached by studs A⁵ and nuts A⁶ to the main frame of the instrument, blocks A⁷ 95 of rubber or other sound-deadening material being interposed between the action main frame and the main frame of the instrument, which latter main frame is not shown, as it forms no part of my invention.

The action main frame lies in front of the main frame of the instrument, and of course in front of the strings, the main frame of the piano being inclined from the vertical at

an angle shown by the string in Figs. 2 and 3, so as to bring the string close to the hammers above and enable them to clear the wheels d , e , and f below.

5 Retaining-boxes b b in line with each other are attached to the main frame by studs and bolts. In these boxes the traction-shaft or friction-driver C is set. When the mechanism is adjusted as it should be no part of the weight 10 of the friction-driver C falls on the boxes b b . They serve only to retain it in its proper position to prevent the displacement of it. Hence I call them "retaining-boxes." There is nothing peculiar in the construction of 15 these boxes. Any suitable form of box or journal may be used. Three boxes c c c , exactly similar to each other, are mounted upon stud-posts c^3 c^3 c^3 , so as to be capable of swiveling thereon. The stud-posts c^3 c^3 c^3 are 20 attached to the main frame A by nuts c^4 c^4 c^4 , (not seen in the main view,) while similar nuts c^4 c^4 c^4 serve to retain the boxes c c c , respectively, on their stud-posts. A supporting-wheel d lies immediately under the center 25 of gravity of the friction-driver C . A shaft d' is attached fast to the wheel d . Said shaft d' passes through the vertically-movable retaining-box d^2 and through the swiveling box c . It rests upon the supporting-wheel e . A shaft e' is attached fast to the wheel e . Said shaft e' passes through a vertically-movable retaining-box e^2 and through the swiveling box c' . It rests upon a supporting-wheel f . A shaft f' passes through 30 a vertically-movable retaining-box f^2 and through the swiveling box c^2 . A weight-wheel d^3 , having a hub d^4 , is attached to the shaft d' , and a similar but heavier weight-wheel, e^3 , having a hub e^4 , is attached to the shaft e' . 35 g , g' , g^2 , g^3 , g^4 , g^5 , and g^6 are collars attached to the shafts d' , e' , and f' by set-screws. (Not shown in the drawings.)

Displacement of the shaft d' in the line of its axis is prevented by the hub d^4 and the 45 collar g , which lie on opposite sides of the box c and in close proximity to it.

Displacement of the shaft e' in the line of its axis is prevented by the hub e^4 and the collar g' , which lie on opposite sides of the box c' and in close proximity to it.

Displacement of the shaft f' in the line of its axis is prevented by the collars g^2 and g^3 , which lie on opposite sides of the box c^2 and in close proximity to it.

55 The retaining-boxes d^2 e^2 f^2 , respectively, are prevented from displacement in the lines of the axes of their respective shafts d' , e' and f' by the collars g^1 , g^5 and g^6 , respectively, and by the greater diameter of their respective shafts d' , e' and f' between said boxes d^2 , e^2 and f^2 , respectively, and the wheels d , e and f , respectively, the diameters of the shafts d' , e' and f' within their respective vertically-movable retaining-boxes being the 60 same as their diameter to the right of such

boxes, while their diameter to the left of said boxes is greater.

The boxes d^2 , e^2 and f^2 are exactly similar to each other and are held in place by the main-frame rib A^3 and the plate A^8 . The latter is held in place by studs A^9 A^9 and retaining-nuts. These studs consist of a central portion of larger diameter and end portions of smaller diameter, threaded at the extremities. They are secured to the main-frame 70 rib A^3 by nuts A^{22} A^{22} , and the distance between the rib A^3 and the plate A^8 is slightly greater than the thickness of the boxes d^2 , e^2 and f^2 , so that said boxes are free to move vertically, but are kept from horizontal displacement. A lever d^5 , swivelingly mounted on a stud-post d^6 and carrying a weight d^7 , exerts a pressure upward on the box d^2 exactly equal to the weight of said box. A similar lever, e^5 , swivelingly mounted on a stud-post 80 e^6 and carrying a similar weight, e^7 , in like manner exerts a pressure upward on the box e^2 exactly equal to the weight of said box. The wheel d^3 is made of such a weight that the shaft d' balances on the supporting-wheel 85 e when the weight of the friction-driver C is resting upon the wheel d . In like manner the wheel e^3 is made of such a weight that the shaft e' balances on the supporting-wheel f when the weight of the friction-driver C and 90 the weight of the shaft d' and the parts attached to it rest upon the wheel e . A weight h is set upon a rod h' , which is attached to a casting h^2 , which is swivelingly mounted on a stud-post h^3 and held in place thereon by a 95 nut h^4 . A push-bar h^5 is attached by the center-pin h^6 to the casting h^2 . The rod h' is threaded and the weight h is adjusted thereon by nuts h^7 and h^8 . The weight h is made of such a mass and is so adjusted on the rod h' 100 that it exerts an upward pressure on the box f^2 , through the push-bar h^5 , exactly equal to the downward pressure on said box of the shaft f' and the parts whose weight it bears. Thus the weight of the friction-driver is borne 105 in the first place by the supporting-wheel d , which transmits it, by the shaft d' , to the wheel e , which in turn transmits it by the shaft e' to the wheel f . It will be seen also that as the parts are proportioned in the drawings 110 the angular velocity of the wheel d is much less than that of the friction-driver C , and the angular velocity of the wheel e is much less than that of the wheel d , and the angular velocity of the wheel f is much less 115 than that of the wheel e . In this manner the friction is very greatly reduced.

D is the key.

E is the hammer; E', the hammer-shank; E², the hammer-but, which is pin-jointed to the pressure-lever F, which last is attached by a flange G to the action-rail a'. The hammer-but serves as a contact-piece to take power from the friction-driver C. The lower surface of said hammer-but E² is curved, the 120

center from which the curve is described being the center of the pin by which the hammer-butt E² is connected with the pressure-lever F.

5 H is the reach-up, which is pin-jointed to the bridle-levers H' and H², which are attached by flanges H³ and H⁴, respectively, to the action-rails a' and a², respectively. A jack or fly-lever H⁵ is also pin-jointed to the lever H'. An expansive spring H⁶ holds the jack H⁵ normally in contact with the adjustable stop H⁷, which is attached to the rail a' by a screw passing through an elliptical slot in said stop H⁷, whereby adjustment of said stop is made. In 15 its normal position the jack H⁵ lies under the end of the pressure-lever F and in close proximity thereto.

A push-bar K is pin-jointed to the hammer-butt E² below the center of attachment of said 20 hammer-butt with the pressure-lever. A weight K' serves to balance the push-bar on the pin by which it is connected with the hammer-butt E². The pressure-lever F rests normally in contact with the action-rail a³ and 25 holds the curved hammer-butt E² in close proximity to, but free from contact with, the friction-driver C. The front part of the push-bar K lies between the lower surface of the action-rail a³ and the upper surface of the 30 reach-up H. The damper-lever L is attached by a flange L' to the rail a⁴. A spring holds the damper normally in contact with the string M, to which it corresponds. A push-bar L³ is connected with the damper-lever and arranged 35 in the path of motion of the hammer-butt, so that the hammer's movement toward the string withdraws the damper from contact with the string.

The shaft C is rotated in a suitable manner. The means of rotating it will be obvious to any one skilled in the art. In some situations an electric motor may be most conveniently employed. An ordinary foot-pedal may be used, or a water-motor may be employed. The shaft must be in some manner rotated; but the mode of rotating it forms no part of the present invention. An improved 45 pedal arrangement for this purpose is described in another application of even date 50 herewith, Serial No. 467,096.

When the key D is depressed by the performer it raises the reach-up H, which through the intervention of the bridle-lever H' and jack or fly-lever H⁵ moves the pressure-lever F from its normal position and presses the curved surface of the hammer-butt E² against the moving friction-driver C, which at once exerts a traction on said hammer-butt approximately proportional to the pressure on 55 the key and throws the hammer toward the string M. As the hammer E moves toward the string, the push-bar K moves toward the jack H⁵, and at or about the instant the hammer strikes the string the push-bar K forces 60 the lever H⁵ out from under the pressure-lever F, which immediately returns to its normal position, raising the hammer-butt E²

from contact with the friction-driver C and so releasing said hammer-butt from the traction of said friction-driver. At the same 70 time the reach-up H, under the influence of the pressure on the key, rises a little and presses the push-bar K against the action-rail a³, by which it is arrested. The hammer now rebounds and retreats from the string a 75 certain distance, the force of the rebound being broken by the friction of the push-bar K against the top of the reach-up H and the bottom of the rail a³, against which it is pressed by said reach-up. In this position the 80 hammer is held until the key is released, when the parts return to their normal positions.

Many modifications of the structure illustrated in Figs. 1, 2, 4, and 5 may be made without departing from some of the essentials of my invention. I shall point out a few of these modifications.

The object of using a train or series of supporting-wheels, as d, e and f, is to reduce with each wheel of the train or series the sum 90 total of the friction; but it is not necessary to employ a train or series of supporting-wheels. In several of the drawings, it will be observed, a single supporting-wheel is used instead of a train; and it will be obvious 95 that in the device of Figs. 1, 4 and 5 the lower wheel, f, with its shaft, boxes, collars and balancing-wheel, might be omitted, the weight-pressed bar h³ being extended up to the box e², or the two lower wheels of the 100 train, f and e, with their shafts, boxes, collars and balancing-wheels, might both be omitted, the bar h⁵ being in such case extended up to the box d². This will be obvious.

Instead of placing the supporting-wheels 105 below the friction-driver, they may be placed above it; and this may be done in at least two different ways: (a) by connecting the supporting-wheel with the friction-driver by a cord, belt or band, on which the friction-driver rests and by which its weight is transmitted to the supporting-wheel, or (b) by furnishing the supporting-wheels with rims, on the inside of which the traction-shaft rests. The first of these arrangements is 110 represented in cross-section and partly in elevation in the detail view, Fig. 6, in which C is the friction-driver; e, the supporting-wheel; e', an endless belt, cord or band connecting them; f, a lever, centered at f', upon 115 which the supporting-wheel e is rotatably mounted; and g is a weight connected with the lever f by an adjustable piece g', and serving to exert upon the friction-driver C, through the wheel e and belt e', an upward 120 pressure equal to the weight of said friction-driver.

Instead of employing a friction-driver incapable of vertical movement and an upwardly-pressed supporting-wheel or supporting-wheels, the supporting wheel or wheels may be made incapable of up-and-down movement and the friction-driver be arranged to rest upon them. This can be done in a variety of 125 130

ways, which it is not necessary to describe in detail. I shall describe one such arrangement only. (See Figs. 8, 9, 10 and 11.) A fixed shaft 2 extends parallel with the friction-driver C, being supported by brackets 3 3, screwed fast to the tops of the upright ribs A A of the main frame. Supporting-wheels 4 4 turn loosely on this shaft. Each of these wheels is furnished with an inwardly-extending rim, (see Figs. 9 and 10,) and on these rims the small turned ends of the friction-driver C rest. The retaining-boxes b b, in which the friction-driver is set, are not fastened to the upright ribs A A, but are held 15 in place between said ribs A A and a flat bar 5, as illustrated in the drawings. The bar 5 is held in place by nuts 6 6, screwed onto studs 7 7. These studs are set fast in the upright ribs A A. Collars 8 8 encircle these 20 studs and hold the bar 5 away from the rib A such a distance that the retaining-boxes b b are free to move up and down, but restrained from motion sidewise. The nuts 6 6 hold the bar 5 tightly against the collars 8 8.

25 I have shown fixed retaining-boxes for the friction-driver and vertically-movable supporting-wheels, and I have also shown supporting-wheels set on fixed axles, the friction-driver being mounted in movable boxes. The 30 object is to prevent displacement of the friction-driver and transfer its weight to a wheel or other suitable angularly-moving surface; and this may be done by suitable means, even though the friction-driver and the supporting 35 wheel or wheels are alike mounted in fixed boxes. It may be done, for instance, by an endless band or belt connecting the friction-driver with the supporting-wheel above it, the band being subjected to such a pressure that 40 its upward pressure on the friction-driver equals the weight of said part. The belt may be subjected to the necessary pressure by a small wheel, spring-pressed against it, as in Fig. 7, in which C is the friction-driver turned 45 small where the belt acts upon it; d, the supporting-wheel mounted upon the shaft d'; d², the belt; d³, the pressure-wheel pressing against said belt; d⁴, a lever upon which said wheel is mounted; d⁵, a bar connected with 50 the frame and into which the shoulder-screw is driven, upon which the lever d⁴ is fulcrumed, and d⁶ an adjustable contractile spring which serves to press the wheel d³ against the belt d² with just so much force that the upward 55 pull of the belt d² on the friction-driver C exactly equals its weight; and many other modifications may be made, too numerous to mention. As springs, for example, are in general interchangeable with weights, it will be understood that the spring used in Fig. 7 might be used instead of the weight in Figs. 1 and 6, and that the weight of Figs. 1 and 6 might be used instead of the spring in Fig. 7. It is entirely immaterial whether a spring or a 60 weight be used; and, indeed, it will be understood from the drawings and the description before given that neither a spring nor a

weight is indispensable to the carrying out of my invention in some of its forms.

I do not claim herein the arrangement of 70 hammer, hammer-butt, lever carrying hammer-butt, escapement and checking mechanism herein described, for that, as before mentioned, forms the subject-matter of another application of even date herewith, Serial No. 75 467,096; but

What I do claim herein, and desire to secure by Letters Patent, is—

1. In a pianoforte - action, a rotatively-mounted friction-driver, circular in cross-section and arranged transversely to the keys of the instrument, and an angularly-moving supporting-surface for said friction-driver. 80

2. In a pianoforte and in combination, a rotatively-mounted friction - driver, circular 85 in cross-section and arranged transversely to the keys of the instrument, retaining-bearings therefor, serving to prevent displacement of said friction - driver, an angularly-moving supporting-surface for said friction- 90 driver, and means serving to press said angularly - moving supporting - surface upwardly against said friction-driver, so that the weight of said friction-driver is borne in whole or in part by said angularly - moving supporting- 95 surface.

3. In a pianoforte - action, a rotatively-mounted friction-driver circular in cross-section and arranged transversely to the keys of the instrument, in combination with a sup- 100 porting-wheel serving to sustain the weight of said friction-driver in whole or in part.

4. In a pianoforte and in combination, a rotatively-mounted friction - driver, circular 105 in cross-section and arranged transversely to the keys of the instrument, retaining-bearings for said friction-driver serving to prevent displacement of said friction-driver, and a supporting - wheel serving to sustain the weight of said friction - driver in whole or in 110 part.

5. In a pianoforte and in combination, a rotatively-mounted friction-driver of circular cross-section, retaining-bearings for said friction-driver serving to prevent displacement 115 of said friction-driver, a supporting-wheel for said friction-driver and means serving to relieve the before-mentioned retaining - bearings (in part or in whole) of the weight of the before-mentioned friction-driver and to transfer the same in whole or in part to the before-mentioned supporting-wheel. 120

6. In a pianoforte and in combination, a rotatively-mounted friction-driver of circular cross-section, a supporting-wheel serving to 125 sustain the weight of the friction-driver in whole or in part, a vertically-movable shaft or axle upon which said supporting-wheel is mounted, and means serving to press said supporting-wheel upwardly, so that the weight 130 of the before-mentioned friction - driver is made to rest in whole or in part upon the before-mentioned supporting-wheel.

7. In a pianoforte and in combination, a

rotatively-mounted friction-driver of circular cross-section, retaining-bearings for said friction-driver, serving to prevent displacement of said friction-driver, a supporting-wheel for 5 said friction-driver, placed below said friction-driver, and means serving to press said supporting-wheel upwardly against the before-mentioned friction-driver, so that the weight of the before-mentioned friction-10 driver is made to rest in whole or in part upon said supporting-wheel.

8. In a pianoforte and in combination, a rotatively-mounted friction-driver circular in cross-section, a supporting-wheel serving to 15 sustain the weight of said friction-driver in whole or in part, and an angularly-moving supporting - surface for said supporting-wheel.

9. In a pianoforte and in combination, a 20 rotatively-mounted friction-driver of circular cross-section; retaining-bearings for said friction-driver, serving to prevent the displacement of said friction-driver; a supporting-wheel for said friction-driver, said support-

ing-wheel having attached to it a circular part 25 of smaller diameter than itself; and a supporting-wheel for said circular part.

10. In a pianoforte and in combination, a rotatively-mounted friction-driver of circular cross-section; retaining-bearings, serving to 30 prevent the displacement of said friction-driver; a supporting-wheel for said friction-driver, said supporting-wheel having a circular part of smaller diameter than itself attached to it; a supporting-wheel for said circular part; and means serving to press the last-mentioned supporting-wheel upwardly, thereby exerting an upward pressure on the friction-driver, and supporting its weight in 35 whole or in part.

In testimony whereof I have hereunto set my hand, at Washington, in the District of Columbia, this 6th day of January, A. D. 1893.

THADDEUS CAHILL.
